(57) **CLAIM**

The ornamental design for a display device with a graphical user interface showing a vehicle navigator traffic level indicator element, as shown and described.

DESCRIPTION

FIG. 1 is a front view of a 1st embodiment of a display device with a graphical user interface according to my design; FIG. 2 is a front view of a 2nd embodiment of a display device with a graphical user interface according to my design; FIG. 3 is a front view of a 3rd embodiment of a display device with a graphical user interface according to my design;

FIG. 4 is a front view of a 4th embodiment of a display device with a graphical user interface according to my design; FIG. 5 is a front view of a 5th embodiment of a display device with a graphical user interface according to my design; FIG. 6 is a front view of a 6th embodiment of a display device with a graphical user interface according to my design; FIG. 7 is a front view of a 7th embodiment of a display device with a graphical user interface according to my design; FIG. 8 is a front view of an 8th embodiment of a display device with a graphical user interface according to my design; FIG. 9 is a front view of a 9th embodiment of a display device with a graphical user interface according to my design; FIG. 10 is a front view of a 10th embodiment of a display device with a graphical user interface according to my design; FIG. 11 is a front view of an 11th embodiment of a display device with a graphical user interface according to my design; FIG. 12 is a front view of a 12th embodiment of a display device with a graphical user interface according to my design; FIG. 13 is a front view of a 13th embodiment of a display device with a graphical user interface according to my design; FIG. 14 is a front view of a 14th embodiment of a display device with a graphical user interface according to my design; FIG. 15 is a front view of a 15th embodiment of a display device with a graphical user interface according to my design; FIG. 16 is a front view of a 16th embodiment of a display device with a graphical user interface according to my design; FIG. 17 is a front view of a 17th embodiment of a display device with a graphical user interface according to my design; FIG. 18 is a front view of an 18th embodiment of a display device with a graphical user interface according to my design; FIG. 19 is a front view of a 19th embodiment of a display device with a graphical user interface according to my design; FIG. 20 is a front view of a 20th embodiment of a display device with a graphical user interface according to my design; FIG. 21 is a front view of a 21st embodiment of a display device with a graphical user interface according to my design; and, FIG. 22 is a front view of a 22nd embodiment of a display device with a graphical user interface according to my design. Throughout the Figures, if and where shown, the broken lines illustrating the display device and portions of the graphical user interface form no part of the claimed design. Portions of the display device and user interface not shown in the Figures and not otherwise described in this specification do not form part of the claimed design.
